ERNEST EDWARD NOBLE, OF FULWELL, SUNDERLAND, ENGLAND, ASSIGNOR TO THE BABCOCK & WILCOX COMPANY, OF BAYONNE, NEW JERSEY, A CORPORATION OF NEW JERSEY

STEAM BOILER

Application filed November 21, 1928, Serial No. 320,838, and in Great Britain December 12, 1927.

This invention relates to improvements in water-tube boilers and more particularly to improvements in water-tube boilers of the Stirling or semi-vertical bent tube type.

5 It is known that steam bubbles ascending through water in a tube produce a movement of the water in the direction in which they travel, and that the most efficient path promoting the greatest velocity of the water is a directly vertical path. It is known also that steam bubbles formed in a horizontal tube will remain at rest in the upper part of the tube, producing no movement of the water or 10 circulating effect in the tube.

15 In tubes therefore which lie close to the horizontal the circulation will be slow and in tubes which lie close to the vertical the circulation rapid.

20 It is an object of the present invention to provide an arrangement of the bank of tubes nearest the furnace of a Stirling or like type of boiler by which the maximum amount of heating surface is obtained in such bank and the maximum amount of such heating surface 25 is exposed to the radiant heat of the combustion chamber.

To this end, in accordance with the invention the tubes or some of the tubes of the front bank of a Stirling or similar bent tube 30 type of boiler are bent intermediate to their terminal bends so that one portion of each such tube of such bank occupies a semi-horizontal position and the other portion of each such tube occupies a semi-vertical position. 35 Preferably, one portion of each such tube lies substantially horizontally over the furnace producing a relatively weak circulation but affording the absorption of the maximum amount of radiant heat, while the other 40 part of such tube is relatively vertical, the relatively vertical portion being of sufficient length to augment the circulation or induce the circulation in the relatively horizontal part of the tubes to the desired acceleration. The semi-vertical part of the tube 45 may be above or below the semi-horizontal part of the tube. In the latter case, the high velocity circulating portion of the tube impels the slower circulation to greater velocity.

Generally, the ends of the tubes of boilers of the type referred to are bent to enter the drums radially and the tubes of the bank nearest the furnace will thus ordinarily have three bends in their length but one only 55 when the drums are so arranged that the axis of each straight part of the tube will pass through the centre of the drums into which they were expanded, or two bends 60 when the axis of one leg of the tube passes through a drum centre. The tube bend of the present invention is one purposely formed for the purpose described of producing a more active circulation in a tube 65 which would otherwise tend to be steam-congested owing to relatively slow circulation.

The invention is illustrated in the accompanying drawing in which the figure is a longitudinal section of a Stirling boiler with 70 the tubes of the bank nearest the furnace constituted in accordance with this invention, the semi-horizontal part of such tubes being located beneath the substantially vertical part of the tubes.

75 Referring to the figure, 10 and 11 indicate the steam and water drums and 12 the mud drum. The two steam and water drums 10 and 11 are connected by a bank of tubes 13, and the steam and water drum 11 is connected to the mud drum 12 by spaced banks of tubes 141 and 142, between which is disposed a transverse superheater indicated generally at 15. In the embodiment of my invention illustrated in the figure, the tubes of the bank 80 142 located nearest the furnace are bent at 85 16 intermediate the usual terminal bends so that each tube is provided with a portion 17 which is more nearly horizontal than vertical of considerable extent over the furnace where 90 it receives the maximum amount of radiant heat, and a vertical or nearly vertical portion 18 serving to induce or increase a circulation in the portion 17 in which the circulation tends to be sluggish. Preferably water cooling tubes 27 extend downwardly from the drum 12 adjacent to the front walls 28 to a header 29. Similarly water cooling tubes 30 extend downwardly from the drum 11 to a header 31, the headers 29 and 31 being con- 95 100

nected by a row of horizontally extending tubes 32 which support the floor 33. The tubes 27, 32 and 30 provide a circulation separate from the boiler circulation. The tubes 5 27 are preferably located in a duct 34, to which air may be supplied from the space 35 beneath the floor of the furnace chamber, and the amount of which may be regulated by a damper 36. Openings 37 are preferably provided 10 in the floor of the furnace, through which air may pass into the combustion chamber, the amount of which is regulated by dampers 38. Air may be introduced into the space 35 by means of doors 39. Auxiliary circulation, 15 however, together with the openings in the floor and the damper regulators constitute no part of my present invention, but are claimed in a separate application.

In the arrangement illustrated in the figure, 20 the gases pass upwardly over the tubes of the lower bank 142, the tubes of the superheater 15, the tubes of the upper bank 141 and are directed downwardly by a baffle 141^a extending from the lower drum 12 along the 25 upper side of the bank of tubes 141, and are then directed over the bank of tubes 13 and tubes 100 which connect the upper drum 10 to the lower drum 12 to an outlet flue 101.

I claim:

30 1. In a low head bent tube boiler and its furnace, an upper drum, a lower drum, a first bank of tubes freely exposed throughout practically all of their lengths to radiant heat from the furnace and bent in different 35 degrees at their ends so that they enter both drums radially, the tubes being bent intermediate their terminal bends to provide horizontally inclined sections extending from the lower drum transversely of the furnace to 40 upright tube sections located between vertical planes bounding the upper drum and extending to the upper bent ends to utilize a density differential which induces in the horizontally inclined sections a flow sufficient 45 to prevent excessive heat damage, a superheater located immediately above the horizontally inclined tube sections, and a second bank of tubes joining the drums and shielded from radiant heat from the furnace only by 50 the first bank of tubes and the superheater.

2. In a steam boiler and its furnace, an upper and a lower drum, a bank of tubes connecting said drums, said bank being divided into an upper group and a lower group with 55 a space between the two, said lower group having a fewer number of rows of tubes than the upper group, each tube of the lower group being bent intermediate its ends to form one portion that is more nearly horizontal than 60 vertical and forming the major portion of the length of the tube and located above the furnace, and another adjacent portion that is more nearly vertical than horizontal, the more nearly vertical portion being of sufficient length to induce or increase the cir-

culation in the more nearly horizontal portion of the tube, and a superheater located in the space between the two portions of said bank.

3. In a steam boiler and its furnace, an upper and a lower drum, a bank of tubes connecting said drums, said bank being divided into an upper group and a lower group with a space between the two, said lower group having a less number of rows of tubes than the upper group, each tube of the lower group being bent intermediate its ends to form one portion that is more nearly horizontal than vertical and forming the major portion of the length of the tube and located above the 70 furnace chamber, another portion located at the upper end that is more nearly vertical than horizontal, the more nearly vertical portion being of sufficient length to induce or increase the circulation in the more nearly horizontal portion of the tube, and a superheater located in the space between the two portions of said bank, all of the gases from 75 said furnace flowing across said boiler and superheater tubes.
